(57) **CLAIM**

The ornamental design for a circular light, as shown and described.

DESCRIPTION

FIG. 1 is a front perspective view of a first embodiment of a circular light;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof;

FIG. 7 is a bottom plan view thereof;

FIG. 8 is a front perspective view of the first embodiment of the circular light shown in use;

FIG. 9 is a front perspective view of a second embodiment of a circular light;

FIG. 10 is a front elevational view thereof;

FIG. 11 is a rear elevational view thereof;

FIG. 12 is a first side elevational view thereof;

FIG. 13 is a second side elevational view thereof;

FIG. 14 is a top plan view thereof;

FIG. 15 is a plan bottom view thereof; and,

FIG. 16 is a front perspective view of the second embodiment of the circular light shown in use.

The broken lines shown in the figures depict portions of the circular light that form no part of the claimed design.

1 Claim, 16 Drawing Sheets
